UNITED STATES PATENT OFFICE.

FRANK M. FABER, OF CANTON, OHIO.

METHOD OF AND APPARATUS FOR MAKING MOTION-PICTURE FILMS.

1,143,522.

Specification of Letters Patent. Patented June 15, 1915.

Original application filed September 15, 1913, Serial No. 789,778. Divided and this application filed October 31, 1914. Serial No. 869,584.

To all whom it may concern:

Be it known that I, FRANK M. FABER, a citizen of the United States, residing at Canton, in the county of Stark and State of Ohio, have invented a certain new and useful Method of and Apparatus for Making Motion-Picture Films, of which the following is a specification.

The invention relates to photographic methods and apparatus for making a motion picture film, which after being exposed and developed in the usual manner, is known as the negative from which a positive is made for producing the appearance of objects in motion, when projected upon a screen by a properly designed stereopticon.

The object of my invention is to imprint on the margins of all or a part of the individual pictures of the film, a title or description of the scene or action portrayed, which title changes with the scene or action.

The invention may also be employed to advantage in the production of certain kinds of so-called trick pictures, wherein effects are now produced by double exposure or double printing, as in the production of so-called spirit pictures or ghosts; and also in the production of dissolving views.

Heretofore, the scenes or actions displayed at moving picture exhibitions, have been described or explained to the audience either by word of mouth, or by projecting upon the screen in advance of the projection of the picture, a title descriptive in more or less detail of the scenes or action to follow; it being understood that when the latter method has been employed, the title or descriptive matter has not been displayed contemporaneously with and in correspondence with the scene or action. The latter method, though almost universally employed, is unsatisfactory for the reason that the distinct events or objects of interest displayed are frequently so great in number and occur in such rapid succession, that it would overtax the capacity of the ordinary observer to carry in mind and properly apply the full description, given before hand, of so rapidly changing a succession of events.

By way of illustration, reference is made

to the views taken from a rapidly moving railroad train, such as are frequently displayed, wherein points of interest succeed each other in rapid succession, and though a full description displayed before hand would be of small value to an audience for reasons stated above, it would not be practicable to break the scene and display, in the usual manner, the title description of each succeeding object of interest. Again, in the so-called moving picture plays, the actors are frequently seen to converse, while the audience is in ignorance of what they are saying. Finally the element of interest in many of the incidents of such plays is lost, since the story told in advance precludes the possibility of surprise. So that an important object of my invention is, in great measure, if not entirely, to dispense with the present method of interrupting the scenes from time to time to interpolate titles descriptive of what is to follow; and to provide a film which will project simultaneously upon a screen a changing scene and a title descriptive thereof, said title changing in correspondence with the scene.

The improved apparatus is preferably made by adding to the motion picture taking apparatus in common use, a supplementary lens or lenses, which supplementary lens is focused on a part of the film, either adjacent to, at a distance from, or coinciding with the part thereof upon which the principal lens is focused, with the object of imposing on the sensitized film a photographic imprint of separate scenes presented to the two lenses respectively, either by simultaneous action of both lenses on the same or different parts of the film, or of imposing a photographic imprint on the film of the scene presented to the supplementary lens on a part of the film adjacent to but not included in the part of the sensitized film affected by light passing through the principal lens. Several forms of such an apparatus are illustrated in the accompanying drawings, forming part hereof, in which—

Figure 1 is a sectional view of a moving picture taking machine showing the supplemental features thereof partly in section and partly in perspective; Fig. 2, a vertical

sectional view of the supplemental feature; Fig. 3, a modified form of the apparatus in sectional elevation; Fig. 4, a section of another modified form of the apparatus;

- 5 Fig. 5, a plan view, showing certain parts in section on line 5—5, Fig. 4; Fig. 6, a form of screen or shutter used in connection with the form of apparatus shown in Figs. 4 and 5; Fig. 7, another modified form of 10 the apparatus; and Fig. 8, a fragmentary view of the finished film made by the improved method.

Similar numerals refer to similar parts throughout the drawings.

- 15 1 is the motion picture camera obscura having light tight walls; 2, the film which moves in the direction indicated by the arrow; 3 and 4, the feed rolls; 5, the loop formed in the film; 7, a beater mechanism 20 for imparting the intermittent motion to the film; 8, the revolving shutter for screening the film when in motion and exposing it when stationary; 9, the principal lens; 10, the film gate; 11, the principal window 25 therein for the principal lens; and 12, the tension plate for keeping the film flat and in alinement. These parts constitute the main elements of a type of moving picture taking machine in general use.
- 30 For the purpose of affixing titles to the individual pictures of the scenes or actions, as the same are being taken on the film by the principal lens, it is preferred to use the arrangement shown in Fig. 1, in which the 35 supplementary lens 13 is focused on the film at a supplementary window 14 located in the gate to expose a part of the film which will advance to and coincide with or be adjacent to the part thereof which will be exposed to 40 the principal lens.

The light tight compartment or extension 15 is attached to the principal camera obscura, and with the lens 13 forms a supplementary camera obscura external to this 45 principal camera obscura. Within the supplementary camera obscura is provided the inclined mirror 16 opposite the window 17 thereof, and 18 is a strip of transparent or preferably translucent material on which is 50 inscribed continuously and in proper sequence, descriptive matter of the scenes or actions to be photographed.

55 19 and 20 are reels on to and from which the strip 18 may be rolled by turning the cranks 19^a and 20^a. The reels are supported by suitable brackets 22 attached to the extension 15, and the strip 18 slidingly fits the grooves 23 in the sides of the window 17.

60 24 is a shutter with which the window 17 may be closed.

65 The arrangement illustrated in Fig. 1 provides means for photographing on all or a part of the margins of the pictures on successive sections of the film, successive titles or inscriptions descriptive of the changing

scenes portrayed, so that such successive titles or inscriptions will be exhibited simultaneously and with the changing scenes which they respectively describe.

For operating the apparatus, the descriptive matter of the scenes or actions to be photographed are inscribed upon the strip 18 in the order in which they will occur; the words being either clear on a dark background or dark on a clear background. 70 Light passing through the strip 18 is reflected by the mirror 16 through the supplementary lens 13, the image of the strip 18 being focused on the part of the sensitized film at the window 14. As the scene changes 75 or the action progresses, the title bearing strip 18 is drawn past the window by turning one of the cranks, so as to suit the word to the action. The distance from the bottom of the window 14 to the top of the window 80 11, is equal to the distance, or a multiple of the distance, which the film advances in each successive movement; consequently, when the machine is in operation, the latent image 85 impressed upon the sensitized film at the window 14 by the supplementary lens will, after having advanced the intervening intervals, occupy a position above and adjacent to the window 11, through which window the latent image of the scene being 90 photographed is impressed by the principal lens 9, and the next successive movement of the film carries the part of the film impressed by the supplementary lens, beyond the window 11. Thus the image of the title 95 or inscription on the strip 18 will, when the film is developed, appear on the margins of the pictures due to the principal lens 9, as shown in Fig. 8, wherein the relative change 100 in the positions of the scenes and titles are 105 greatly exaggerated.

The resulting picture will, when projected upon a screen in the usual manner, appear to the observer as having a descriptive title 110 on the margin, and if the title bearing strip 115 18 be kept in motion while the views are being taken, the title is finally projected upon the screen, will appear to move from right to left along the margin of the picture; so that a title longer than the width of the 115 picture, can be read as it passes slowly along the margin thereof. It is evident that the title may be made to appear either at the top, bottom or sides of a picture, or that by changing the position of the supplementary 120 lens 13 and window 14 relatively to the lens 9, that is, by lengthening or shortening the vertical distance between them, when the scene is being photographed, the title may be made to appear superimposed upon the 125 face of the picture.

The reading matter on the strip 18 may be a simple title, or a more or less lengthy description of the scene, or it may be the words spoken by the characters in the scene. It is 130

evident that the window 17 and the strip 18 might be located immediately in front of the lens, and the mirror 16 dispensed with; but if so located, the extension 15 would 5 more or less obstruct the view of the principal lens 9 and would moreover render the outfit less compact..

In the modified form of apparatus shown in Fig. 3, the light tight compartment 15^a, the supplementary lens 13^a, the supplementary window 14^a formed in the tension plate 12^a, and the strip 18^a comprising the supplementary camera obscura, are on the opposite side of the film from the principal 15 camera obscura. For this arrangement I add a revolving shutter 8^a which performs the same function as the shutter 8 and acts in unison therewith; and the light acting on the sensitized emulsion, passes through the 20 film, which is transparent, as will be understood. It is evident that a mirror may be employed in this modification to reflect the light from a window equivalent to 17 located at the top, bottom or either side of the 25 camera. It is also evident that the lengthy strip 18 may be moved intermittently as the scene or action may require, or may be replaced by a series of short strips similar to the so-called lantern slides used in the stereopticon.

In the modified form of apparatus shown in Figs. 4, 5 and 6, the supplementary lens 13^a and window 14^a may be located as in Fig. 3; and a second supplementary lens 13^b 35 and a reflecting mirror 16^a are provided, the lens 13^b being preferably of the same size as the principal lens 9, and the distance between the axes of these lenses and the center of the corresponding windows 11 and 14^b is 40 equal to a multiple of the distance which the film advances in each successive movement. Consequently, when the machine is in operation, the latent image, hereinafter referred to as the supplementary image, formed on 45 the sensitized film by lens 13^b focused on the scene 30, hereinafter referred to as the supplementary scene, is, after having moved a certain number of increments, advanced to the space directly behind and coinciding 50 with the window 11, when the latent image, hereinafter referred to as the principal image, formed by lens 9 focused on the scene 31, hereinafter referred to as the principal scene, is superimposed thereon. 55 Between the lenses 9 and 13^b and the film, may be extended the opaque screen 25 in the grooves 26, which screen is provided with the diagonally opposed openings 27 and 28. The inner edges of these openings 60 are serrated as indicated, and the vertical distance between the openings is equal to the distance between the centers of the lenses 9 and 13^b. The rod 29 is attached to the screen 25, which rod projects through the 65 side of the camera for the purpose of mov-

ing the screen back and forth past the lenses in grooves 26.

When the screen 25 is moved past the lenses, the light is gradually shut off from one lens while it is gradually admitted to 70 the other, and as the successive images formed by the one lens will gradually fade into darkness, those formed by the other lens will gradually increase from darkness to full brilliancy; it being understood that while the shutter 25 is being moved past the lenses, the film makes several successive movements, and that consequently several individual pictures will be imposed upon the film by each lens. Since the views imposed 75 on the films by the two lenses are superimposed, as has been described, the so-called dissolving view effect will be obtained, when the picture is projected on a screen in the usual manner, and it is evident that the same 80 effect may be attained without the use of a screen by gradually illuminating one of the scenes 30 or 31 upon which the lenses are focused, while the other is gradually and simultaneously darkened.

In producing ghost or spirit pictures, so-called, with this modification of the device, where a ghost is made to appear and disappear, during a dramatic performance, the screen 25, is dispensed with, and one of the 90 lenses, say 13^b, is covered by a cap or provided with a shutter; the actor personating the ghost is clad in light colored garments, and stationed say at 30, Fig. 5, and his image is focused on the film by the lens 13^b, 95 the background (not indicated in the drawing) being black so that the image of the ghost only will be imposed on the film. The theatrical performance, including scenery, etc., takes place at 31, Fig. 5, and its image 100 is formed on the film by lens 9. With the camera thus arranged, the image of the ghost may be gradually or suddenly thrown upon and withdrawn from the film by gradually or suddenly uncapping the lens 13^b, or 105 manipulating its shutter. It is evident that the same effect can be obtained by illuminating or darkening the ghost.

In the modified form of apparatus shown in Fig. 7, the lens 9 and the second supplemental lens 13^c and their corresponding windows 11 and 14^c respectively, are directly opposite each other and simultaneously focus on opposite sides of the same part of the sensitized film; and the supplemental 115 lens 13 and its window 14 may be arranged as in Fig. 1, it being understood that a screen, not shown, of the general character shown in Fig. 6, may be employed for dissolving the views opposite lenses 9 and 13^c. 120 With this modification we have the dissolving view effect with the title changing simultaneously, and in accordance therewith.

It is evident that when the supplemental lens 13, 13^a or 13^b is arranged as in Figs. 1, 125

4, 5 and 7, the interval of time between the exposure of the film through the lens 13 and the exposure of the same picture field of the film through the lens 9 is so slight, that the 5 exposure is either simultaneous or with a negligible difference of time; and in all forms of the apparatus shown and described herein, the simultaneous exposure of the film through all of the several lenses to all 10 of the several views, are either upon the same or adjacent parts of the film, and are included within that section of the film which is projected, for exhibition purposes, upon a screen at the same instant by a single lens, which section of the film is herein 15 referred to as a picture field of the film.

In the arrangement shown in Fig. 1, the focal length of lens 13 is preferably shorter than that of lens 9 so that the title on strip 20 18, may, for convenience, be printed on an ordinary typewriter and yet be so reduced in size on the film as to be of minimum height; and it is evident that when employing three or more lenses all may be of different focal lengths as circumstances may 25 require. The revolving shutter 8 and also its companion 8^a may be of the usual broken disk type, and it will be understood that the wings of the disk or disks are so related as 30 to expose the portion of the film at all of the windows 11, 14 and 14^a at and during the same short interval of time. It is also evident that though, in the arrangement shown in Fig. 1, the images of the title and 35 the view which appear in juxtaposition on the negative are formed or exposed during the same interval of time, the title was formed, one or more intervals of exposure before its respective picture was formed.

40 In the foregoing, I have described the moving picture taking apparatus in which the film has an intermittent movement, but it is evident, to those skilled in the art, that my device may, with proper modifications, 45 be embodied in cameras in which the movement of the film is continuous.

It will be understood that the distinctive 50 feature of this invention, is the apparatus for exposing the sensitized film of a moving picture taking apparatus to a plurality or a multiplicity of scenes, each scene being focused on the film by a separate lens, and each scene being out of the field of view of all lenses, excepting the one which focuses 55 its image on the film; which is accomplished by combining a plurality of cameras obscura in the same apparatus, each one external to the others, but so arranged that

the various lenses will focus the images of a plurality of different scenes on the same picture field of the film. 60

It is evident that should the entire camera be moved while in process of taking pictures, as when being carried on a vehicle or moved upon its base to "panorama" a scene, 65 such movement will not displace the image of the title on the film, since the title is attached to and carried with the camera by means of the brackets 22 and the grooves 23.

This application is a division of my former application filed September 15, 1913, Serial No. 789,778, for method of making motion picture films. 70

I claim:

1. The method of making motion picture 75 films consisting in exposing successive picture fields thereof in rapid succession through a plurality of separate lenses to a plurality of separate changing scenes, the exposure of a given picture field through 80 one lens being differentiated in time from its exposure through another lens.

2. The method of making photographic 85 films for the exhibition of objects in motion, consisting in passing a sensitized film across a principal lens at a high rate of speed and with an intermittent motion, and exposing successive fields of projection of the film during periods of rest to a scene of action, and exposing the same picture fields 90 to a different scene through a supplementary lens, one of the lenses acting on a portion of the film one or more increments of movement in advance of the portion of the film exposed to the other lens. 95

3. In a photographic apparatus, means for intermittently moving a sensitized film, a principal camera obscura arranged to focus the image of a scene upon one picture field of the film during a period of rest, a 100 supplementary camera obscura arranged to focus the image of a different scene on another picture field of the film during the same period of rest, the movement of the film between periods of rest being such that 105 the image focused by one camera obscura upon each picture field is superposed upon the image focused by the other camera obscura, whereby one camera obscura will act upon a given picture field of the film one or 110 more increments of its movement in advance of the other camera obscura.

FRANK M. FABER.
